UNITED STATES PATENT OFFICE.

JONATHAN JOHNSTON, OF MORGAN PARK, ILLINOIS, ASSIGNOR TO
HERBERT O. BENNETT, OF CHICAGO, ILLINOIS.

DESIGN FOR A BASE FOR OIL-BURNERS.

SPECIFICATION forming part of Design No. 27,177, dated June 8, 1897.

Application filed April 19, 1897. Serial No. 632,873. Term of patent 7 years.

To all whom it may concern:

Be it known that I, JONATHAN JOHNSTON, a citizen of the United States, residing at Morgan Park, in the county of Cook and State of Illinois, have invented and produced a new and original Design or Useful Shape for the Base Portions for Oil-Burners, of which the following, in connection with the accompanying drawings, is a full, clear, and exact specification.

In the said drawings, Figure 1 is a plan view of the base portion of an oil-burner embodying my design. Fig. 2 is a front elevation thereof. Fig. 3 is a transverse sectional view taken on the line 3 3, Fig. 1; and Fig. 4 is a detail transverse sectional view taken on the line 4 4, Fig. 1.

The leading feature of my design consists of the base portion of an oil-burner having formed in its outer edge the annular channel A and another annular channel or depression B, surrounded by the channel A and in turn surrounding the central cavity or countersink C.

The bottom of the channel A is semicylindrical in cross-section, as shown in Fig. 3, and when viewed in plan, as in Fig. 1, it presents the appearance of two concentric rings or annular flanges *a b*, which constitute the outer and inner margins of the channel A. The ring or flange *b* also constitutes the outer margin or wall of the annular depression B, while the inner wall of such depression is constituted by the annular flange-like portion or ring *c*, and the opposed faces of these two rings or flanges *b c* are precipitous or sub-

stantially vertical, as indicated in Fig. 3. The ring B has projecting from its outer side a number of radial lugs D, which extend into and part way across the channel A and whose upper outlines are downwardly curved, as illustrated in Fig. 4.

When viewed in side elevation, as illustrated in Fig. 2, the outer wall of the ring *a* curves under toward an annular foot portion E, which is of cylindrical formation and constitutes the bottom part of the base, and projecting laterally from this portion E is a cylindrical portion F and a pan-like portion G, arranged in juxtaposition to the portion F, the two portions F and G being connected by a web II. The end of the portion F is provided with a substantially semicircular flange or disk I, having a central perforation J and a peripheral notch K appearing therein when viewed in side elevation, as in Fig. 2. The bottom of the pan-like portion G is also of cylindrical formation, as appears in side elevation in Fig. 2. Back of the flange I the ring *a* is cut away between the points *a'* and *a''*, as appears in side elevation in Fig. 2.

Having thus described my invention, what I claim as new therein, and desire to secure by Letters Patent, is—

The new and original design or useful shape for a base for oil-burners, substantially as herein shown and described.

JONATHAN JOHNSTON.
